ATTORNEY

UNITED STATES PATENT OFFICE.

FRANK M. BOMENBLIT AND DAVID PINK, OF NEWARK, NEW JERSEY.

DESIGN FOR A SIDEBOARD ORNAMENT.

SPECIFICATION forming part of Design No. 35,586, dated January 14, 1902.

Application filed July 19, 1901. Serial No. 68,986. Term of patent 3½ years.

To all whom it may concern:

Be it known that we, FRANK M. BOMENBLIT, a citizen of the United States, and DAVID PINK, a subject of the Emperor of Austria-Hungary, both residing at Newark, in the county of Essex and State of New Jersey, have invented and produced a new and original Design for a Sideboard Ornament, of which the following is a specification, reference being had to the accompanying drawings, forming part thereof.

Figure 1 is a front elevation of a sideboard ornament, showing our new design. Fig. 2 is an end view of the same.

As shown in the drawings, the leading or material feature of our design consists of a rectangular base *b*, the sides of which are formed in double ogee curves, with beveled top and bottom edges. This base is support-

ed at its corners by legs having two extensions at right angles to each other which terminate at the foot of the leg in ogee curves, and a series of glasses *a*, arranged pyramidally upon and formed integral with the base.

Having described our invention, what we claim as new, and desire to secure by Letters Patent, is—

The design for a "sideboard ornament," as herein shown and described.

In testimony whereof we have signed our names to this specification in the presence of two subscribing witnesses.

FRANK M. BOMENBLIT.
DAVID PINK.
